UNITED STATES PATENT OFFICE

148,352

DESIGN FOR AN AUTOMOBILE SEAT COVER OR SIMILAR ARTICLE

Irving Herman, Chicago, Ill.

Application November 10, 1947, Serial No. 142,452

Term of patent 14 years

(Cl. D14—6)

To all whom it may concern:

Be it known that I, Irving Herman, a citizen of the United States, and residing in the city of Chicago, county of Cook, and State of Illinois, have invented a new, original, and ornamental Design for an Automobile Seat Cover or Similar Article, of which the following is the specification, reference being had to the accompanying drawing forming a part thereof. This application is a continuation in part of applicant's presently pending applications for design patents, Serial No. D. 127,806 and No. D. 129,265.

On the drawing:

Fig. 1 is a perspective view of my novel automobile seat cover or similar article, embodying my novel design.

Fig. 2 is an enlarged cross sectional view of a part thereof taken substantially on line II—II of Fig. 1.

The dotted line showing in Figure 1 is for illustrative purposes only.

I claim:

The ornamental design for an automobile seat cover or similar article, substantially as shown and described.

IRVING HERMAN.
